FIRE ALARM

George Rushing, Jr., Little Rock, Ark.

Application April 24, 1944, Serial No. 532,452

2 Claims. (Cl. 177—355)

This invention relates to fire alarms.

An object of this invention is to provide a fire alarm including an normally set spring operated audible signal device which is held in set position by fusible means so that when the latter becomes fused the alarm will be sounded.

Another object of this invention is to provide in a device of this kind a spring operated audible signal device which is held against operation by means of a spring-pressed trigger, the trigger also holding inoperative a spring-pressed starter which will assure the initial operation of the signal device.

A further object of this invention is to provide in combination with a spring-operated signal device and a spring-pressed starter, an electric signal circuit including a switch disposed in a position whereby release of the starter by the trigger will automatically move the switch to circuit closing position so that a remote audible or visible signal may be operated at the same time that the first signal is operated.

A further object of this invention is to provide an audible alarm of this type wherein the alarm device may be placed in a closed housing and sound conducting ducts extended from the housing to remote points so that the sound may be readily heard throughout a building. Where a building is equipped with hot air ducts, the housing may be connected to such ducts from a central point so as to eliminate the placement of additional ducts.

A further object of this invention is to provide an alarm assembly in which a number of the parts making up the assembly may be well known parts which are combined in a manner to produce the desired result.

To the foregoing objects and others which hereinafter appear the invention consists of the novel construction, combination and arrangement of parts as will be more specifically referred to and illustrated in the accompanying drawings, wherein is shown an embodiment of the invention, but it is to be understood that changes, modifications and variations may be resorted to which fall within the scope of the invention as claimed.

In the drawings:

Figure 1 is a detail top plan partly broken away of a fire alarm constructed according to an embodiment of this invention.

Figure 2 is a fragmentary front elevation of the device.

Figure 3 is a detail top plan partly broken away and in section of the device.

Figure 4 is a sectional view taken on the line 4—4 of Figure 1.

Figure 5 is a fragmentary vertical section similar to Figure 4, but showing the trigger and trigger release lever in dotted lines and the starter in dotted position to operate the electric signal switch, and

Figure 6 is a fragmentary sectional view taken on the line 6—6 of Figure 3.

10 Referring to the drawings, the numeral 10 designates generally a housing which is of rectangular form including a bottom wall 11, opposite side walls 12 and 13, opposite end walls 14 and 15, and a top wall 16. The housing 10 has mounted on the inner side of the side wall 12 a bell or audible signal member 17 which is secured to the side wall 12 by fastening members 18 and spaced from the wall 12 by spacers 19.

20 A motor 20 is secured to the inner side of the bottom wall 11, and in the present instance, the motor 20 is a spring motor having a winding shaft 21 extending through an opening 22 formed in the side wall 13. A crank 23 is adapted to 25 be engaged with the winding shaft 21 so as to wind the motor 20. The motor 20 includes a vertically disposed shaft 24 on which a clapper generally designated as 25 is secured. The clapper 25 includes a plate 26 having a boss 27 secured by a set screw or fastening member 28 to the shaft 24. A rod 29 extends from the plate 26, and as shown in Figure 6, is formed with a reverted outer end 30 on which a clapper or striker 31 is loosely mounted.

35 The striker 31, in the present instance, is formed of a cylindrical body which is slidable on the reverted portion 30 of the rod 29. The striker 31 is adapted, upon rotation of the shaft 24, to strike the bell 17 at diametrically opposed points and to continue the striking of the bell 17 when the motor 20 is operative.

A spring-pressed starter generally designated as 32 is adapted to engage within the outer end of the striker 31 and includes a base 33 secured by fastening members 34 to the inner side of the end wall 14. A U-shaped member 35 is pivotally carried by the base 33 and is constantly urged in a direction towards the base 33 by means of a spring 36. In normal position, the U-shaped member 35 is adapted to extend partly into the outer end of the striker 31 as shown in Figure 6 so that when the U-shaped member 35 is released by the trigger to be hereinafter described, the spring 36 will swing the U-shaped member 35 of starter 32 in a counterclockwise direction

as viewed in Figure 3, and initially provide for rotation of the shaft 24 and rotation of the clapper 25.

The starter is normally held in set position by means of a trigger 37 which is pivotally mounted on a pivot member 38 carried by a mounting 39 fixed to the inner side of the side wall 13. The trigger 37 is provided with a bill 40 engaged over the upper leg or side 41 of the U-shaped member 35, as shown in Figure 6, so that the U-shaped member 35 will be held at substantially right angles to the base 33. The trigger 37 projects from the pivot member 38 through an opening 42 formed in the side wall 13 and is provided on the projecting end 43 thereof with a plate or cam member 44 mounted on an angle to the vertical.

A trigger releasing lever 45 is rockably mounted on a pivot member 46 carried by a mounting 47 which is secured to the outer side of the side wall 13. The lever 45 is constantly urged to trigger releasing position by means of a spring 48. The lower end of the lever 45 is rounded off, as at 49, and is adapted to slide over the inclined upper side of the plate 44. The plate 44 may be of any desired length extending from opposite sides of the trigger extension 43 so that several trigger releasing levers 45 may be secured to the housing 10.

In Figures 1 and 3, there are shown two levers 45 which are adapted, when released by the fusible holder, to strike the plate 44 and rock the trigger 37 at its inner end to a released position. The lever 45 is normally held in a disengaged position with respect to the plate 44 by means of an elongated flexible and fusible member 50. The fusible member 50 is connected at one end 51 to the upper end of the lever 45 and the opposite end of the fusible member 50 is connected as at 52 to one end of a pivoted link 53. The link 53 is pivoted as at 54 on a support 55 which is remote from the housing 10 and the opposite end of the link 53 has connected thereto a second fusible member 56.

The fusible member 56 may be extended beyond the link 53 to any desired portion of a building and the opposite end is fixedly secured to a stationary support. The fusible member 56 extends in a direction parallel with one of the fusible members 50, whereas a second link 53a is connected to a second fusible member 50a, and the link 53a has connected to the opposite end thereof a second fusible member 56a. In the present instance, the second fusible member 56a is shown as extending in alignment with the length of the link 53a, but it will be understood that the fusible member 56a may be extended from the link 53a at any desired angle.

A switch 57 is secured by fastening members 58 to the inner side of the end wall 14. The switch 57 includes a pivoted lever 59 which is adapted, upon swinging thereof in a clockwise direction, to close the electric signal circuit. The lever 59 is disposed in the path of the swinging of the U-shaped member 35 so that when this member is released by release of the trigger 37, the member 35 will strike the lever 59 and move this lever to a circuit closing position. An electric alarm circuit 60 is connected with the switch 57 and if desired an audible signal 61 may be interposed in the signal circuit 60 and positioned at any desired point, such as either within or exteriorly of the building or at a point remote from the building.

In the use and operation of this alarm, the fusible members 50 and 50a are extended into the building in which the housing 10 is positioned and

extended about the building to points remote from the housing 10. The fusible members 50 and 50a may be constructed in the form of fusible wire of desired composition, such as lead, solder, or the like, which is adapted to melt when the air in the building reaches a predetermined high temperature.

The fusible members 50 will normally hold the releasing levers 45 in disengaged position with respect to the striker plate 44. The trigger 37 in set position will engage the member 35 and the member will be extended into the outer end of the striker 31. Switch lever 59 will be positioned in the full line position shown in Figure 3 where-in the electric circuit 60 will be broken. In the event any one of the fusible members 50 or 50a, 56 or 56a becomes broken or fused, spring 48 will swing lever 45 and rock trigger 37 at its inner end upwardly to a released position.

At this time member 35 will swing under the action of spring 36 in a counterclockwise direction, starting the swinging movement of clapper 25 and at the same time moving switch lever 59 from a circuit breaking position to a circuit closing position. After clapper 25 has been released and started swinging by the member 35, motor 20 will continue to swing on clapper 25 in a circular path so as to cause the striker 31 to engage the bell 17 at two points on the bell for each complete rotation.

The striker 31 is loosely carried by the arm 29 and is mounted so as to strike the bell 17 at a point below the plane of the horizontal center of the bell. The bell also has a rounded rim which is struck by the striker 31 so that when the striker 31 initially strikes the rounded rim the striker will slide inwardly toward the axis of arm 29 a distance sufficient to permit continued rotation of arm 29. Arm 29 will, thereupon, swing interiorly of bell 17 and strike the opposite edge thereof and at this time striker 31 will also move inwardly so that arm 29 may continue its rotation so as to thereby provide for repeating the bell striking cycle.

In order that the sound of the bell 17 may be carried to various parts about the building with which the fire alarm is associated, I have provided a duct 62, which is connected at one end to the end wall 15, communicating with the interior of the housing 10. The other end of the duct 62 may be connected to a hot air heating system so that the ducts of the heating system will carry the sound to all parts of the building. The duct 62 may also be connected to any other suitable sound conducting pipe for conducting the sound of the bell 17 to points remote from the housing.

This device in view of the motor starter correlated therewith, will provide for positive sounding of an alarm so that if a device should stand for a long period of time and the lubricant for the motor 20 become heavy, and normally prevent operation of the motor, the starter will initially break the lubrication which is heavy and assure proper operation of the motor.

In order to provide a means whereby in the event the motor 20 does not operate the bell 17 may be sounded when the trigger 37 is tripped, I have provided an electrically operated clapper 63 which is connected by conductors 64 to switch 57. In this manner the local sounding of the alarm will be assured as well as the sounding of a remote alarm.

What I claim is:

1. A fire alarm comprising a housing, an audi-

ble signal member in said housing, said member including a motor operated clapper, a pivoted trigger normally holding said clapper inoperative, a spring-pressed lever adapted to engage said trigger to rock the latter to released position, fusible means connected to said lever for holding said lever in disengaged position with respect to said trigger, spring pressed starter means engageable with said trigger and clapper for initially effecting operation of said clapper and motor when said trigger has been moved to released position.

2. A fire alarm comprising a housing, a bell in said housing, a motor in said housing, a clapper

5 rotatably carried by said motor and engageable with said bell, said clapper having an opening in the outer end thereof, a spring-pressed starter carried by said housing having a portion thereof projecting into said opening, a movable trigger normally engaging said starter to hold the latter in set position and simultaneously hold said clapper and motor inoperative, a spring-pressed trigger releasing lever engageable with said trigger to move said trigger to released position, and fusible means connected to said lever to hold the latter disengaged from said trigger.

GEORGE RUSHING, JR.
